UNITED STATES PATENT OFFICE.

HEINRICH A. TH. FRENTZEL, OF BERLIN, GERMANY.

DEVICE FOR ROLLING-IN TUBES.

1,362,935.

Specification of Letters Patent. Patented Dec. 21, 1920.

Application filed October 16, 1916. Serial No. 126,009.

To all whom it may concern:

Be it known that I, HEINRICH A. TH. FRENTZEL, subject of the King of Prussia, residing at Berlin, Germany, Hindersin-
5 strasse 2, have invented certain new and useful improvements in Devices for Rolling-In Tubes, of which the following is a specification.

My invention relates to improvements in
10 a device for rolling in tubes.

The object of the invention is to provide
a device for rolling in tubes which is so
constructed that by means of uniform rollers
the end of the tube is flanged simultane-
15 ously with the expanding of the body thereof
whereby the end of the tube may be
given any desired shape.

In the preferred form of the device ac-
cording to the invention the uniformity of
20 the rollers is obtained by differently form-
ing the mantle of the roller in three parts in
such a manner that each end of the roller
carries a conical member while the middle
25 part is adapted to roll and form the tube.
The conical members serve to give the roller
the required hold upon the conical mandrel
or the like without producing considerable
wear by the edge-contact between mandrel
30 and roller. The middle part of the roller
therefore need not to bear against the man-
drel whereby a great freedom with regard
to the shape thereof is obtained.

In the accompanying drawings a section
35 through a device according to the invention
is shown by way of example.

The example illustrated is based upon the
well-known tube rolling machines in which
three rollers are arranged around a conical
mandrel d located in a casing e . The rollers,
40 of which only one is shown in the drawing,
each consist of the middle part c , the inner
end part c' and the outer end part c^2 . The

end parts c' and c^2 have a common genera-
trix which coincides with that of the man-
drel d . The middle part is so shaped, that 45
it not only expands the tube a in the flange
 b but that it produces at a' a flange of
cambered shape.

I claim—

1. In an apparatus of the class described, 50
the combination with a conical mandrel
adapted to be inserted in the end of a tube
and tapering continuously from end to end
and toward a point lying without the tube,
and a casing surrounding the mandrel, of 55
an expanding roller arranged in the casing
and comprising longitudinally tapering end
sections engaging the mandrel, the taper of
said sections being reversed relatively to the
taper of the mandrel, and an intermediate 60
section shaped to simultaneously expand and
flange the end of the tube engaged thereby.

2. In an apparatus of the class described,
the combination with a conical mandrel
adapted to be partially inserted in the end 65
of a tube, and a casing surrounding the man-
drel, of an expanding roller extending with-
in the casing and comprising longitudinally
tapering end sections, said end sections being
70 portions of a single cone engaging the man-
drel, the taper of said sections being reversed
relative to the taper of the mandrel, and the
section having the greater diameter lying
75 without the casing, and having an interme-
diate section shaped to simultaneously ex-
pand and flange the end of the tube engaged
thereby.

In testimony whereof I affix my signature
in presence of two witnesses.

HEINRICH A. TH. FRENTZEL.
